TUNED ANTENNA SYSTEM

Joseph Ruig Rigandi, Westerleigh, N. Y.

Application October 19, 1936, Serial No. 106,281

7 Claims. (Cl. 250—20)

This invention relates to new and useful improvements in radio apparatus and more particularly it pertains to antenna systems therefor, and this application is a continuation in part of my prior application filed November 30, 1934, Serial Number 755,376, Patent No. 2,058,037, dated October 20, 1936.

10 It is one object of the present invention to provide a new and improved form of antenna which is capable of adjustment and tuning to meet local requirements and particular set conditions.

15 It is a further object of the invention to provide a new and improved antenna system which will materially simplify tuning and improve reception and operation of radio receiving sets.

With the above and other objects in view, reference will be had to the accompanying drawing, in which:

20 Figure 1 is a diagrammatic view illustrating an antenna constructed in accordance with the present invention.

Figure 2 is a diagrammatic view illustrating a modified form of the invention,

Figure 4 is a diagrammatic view illustrating a further modified form of the invention.

Figure 4 is a diagrammatic view illustrating a further modified form of the invention, and;

30 Figure 5 is a similar view illustrating a still further modified form of the invention.

Referring in detail to the drawing and particularly to Figure 1, A designates an induction coil which consists of a primary winding 10 and a secondary winding 11. The primary winding 10 is a continuation of the antenna wire or its lead-in which is herein designated 12. Leading from one end of the secondary winding 11 there is a con-

40 conductor 13 which is electrically connected, as at 14, to the movable member 15 of a variable resistance 16. Interposed in the conductor 13 there is a variable condenser 16 and it will be noted that one end of the primary winding 10 of the induction coil A is electrically connected as at 17 to the conductor 13 at a point beyond the variable con-

40 denser 16. Leading from the secondary winding
11 of the induction coil A, there is a conductor
18 which is connected as at 19 to the ground post
of a radio receiver designated 20. The variable
50 resistance heretofore mentioned is connected at
one of its ends to the antenna post of the receiver
20, the other end being connected to the ground
and interposed between the variable resistance
and the ground there is a fixed condenser 21.

55 From the foregoing it will be apparent that the

variable condenser 16 will serve to tune the antenna circuit to the proper frequency of the receiver and will also act to vary the volume of the set. Furthermore, the volume may also be controlled by operation of the movable member 5 15 of the variable resistance 16.

In Figure 2, the reference character 30 designates an outside antenna, the lead of which is connected to a switch 31 by means of which the antenna may be connected or disconnected with one end of the primary winding 32 of an induction coil B. The reference numeral 33 designates the secondary winding of the induction coil B and one end of this secondary winding 33 is connected as at 34 to a conductor 35 leading from the opposite end of the primary winding 32, and interposed between the secondary winding 33 and the point 34 where it is connected to the primary winding 32, there is a variable condenser 36. Leading from the secondary winding 33 there is a conductor 37 which is connected as at 38 to the movable member 39 of a variable resistance 40. The conductor 35 is connected as at 41 to the ground side of the primary winding 42 of the tube circuit, the secondary winding of this tube circuit being designated 43. The reference character 44 designates a fixed condenser which is electrically connected to the variable resistance 40 and leading from the fixed condenser 44 and electrically connected as at 41 to the ground side of the primary winding 42 of the tube circuit, there is a conductor 45 which is electrically connected as at 46 and 47 to the secondary winding 43 of the tube circuit. Interposed between the two points of connection 46 and 47 there is a variable condenser 48 and in said conductor 45, there is a fixed condenser 49.

In Figure 3, the reference character G designates an induction coil of which 50 is the primary winding, the secondary winding being designated 51. Leading from one end of the winding 51 there is a conductor 52 connected as at 53 to the ground and also to the ground side of the winding H as at 54. The opposite end of the secondary winding 51 has an extension conductor 55 which is connected as at 56 to the primary winding 50 and by the conductor 57 to a conductor 58 which includes the resistance element 59 of a variable resistance, which is also connected to ground at 53. The movable element 61 of the variable resistance is connected by a conductor 62 to the grid 63 of the tube of the first stage of radio frequency.

In Figure 4 I have illustrated a further modification.

fied form of the invention in which there are two antennae employed. The antennae are designated 70 and 71. The antenna 70 is connected by a suitable lead 72 to the primary winding 73 of an induction coil 74, and there is a switch 75 included in this conductor 72. The other end of the primary winding 73 is connected as at 76 to a conductor 77, which in turn is connected to one end of the secondary winding 78 of said induction coil 74, and in this conductor there is interposed a variable condenser 79. The other end of the secondary winding of the induction coil 74 is connected by means of a conductor 80 to a mid-tap 81 in the primary winding 82 of an induction coil 83 and the conductor 77, heretofore mentioned, is connected as at 84 to a mid-tap in the secondary winding 85 of the induction coil 83. The opposite end of the primary winding 81 of the induction coil 83 is connected by a lead 86 with the antenna 71, and this conductor includes a switch 87. One end of the secondary winding 85 of the induction coil 83 is connected by a conductor 88 to the movable member 89 of a variable resistance 90 and this conductor includes a variable condenser 90'. The opposite end of the said secondary winding 85 is connected by a conductor 91 to the movable member 92 of a switch, which movable member is adapted for engagement with a contact 93 from which leads a conductor 94. Leading from the conductor 94 to ground there is a conductor 96 and the resistance element 97 is connected to this conductor 96 as at 98. Leading from the opposite end of the resistance element 97 there is a conductor 99, which is connected to the grid 100 of the first stage of radio frequency of a receiving set. Connected to the conductor 96 as at 101 there is a lead 102 which is connected to the primary winding 103 of an induction coil 104 and the other terminal of said primary winding 103 is connected by a conductor 105 to a conductor 106 leading from the secondary winding 107 of the induction coil 104, and this conductor 105 includes a variable condenser 110. The opposite end of the secondary winding of the induction coil 104 is connected as at 111 to the conductor 99, heretofore mentioned.

By this arrangement it will be apparent that either of the induction coils 74 or 83 may be included in the antenna circuit, or both may be included, or both may be excluded from the antenna circuit. Furthermore, by reason of the fact that the windings of each of the induction coils are electrically coupled, the incoming signal energy of these coils may be varied by the variable condensers in the circuit of each coil.

In Figure 5 I have shown a still further modified form of the invention in which 120 designates an antenna from which extends a lead in 121. The lead in includes a switch 122 and is connected to the primary winding 123 of an induction coil 124. Leading from the opposite end of the primary winding 123 there is a conductor 125, and this conductor 125 is connected as at 126 to the primary winding 127 of an induction coil 128, the connection being made substantially mid-way between the end turns of said winding. The reference numeral 130 designates the secondary winding of the induction coil 124, and extending from one end thereof, there is a conductor 131 which is connected mid-way between the ends of the secondary winding 132 of the induction coil 128. The opposite end of the winding 130 of the induction coil 124 is connected by means of a conductor 135 to the conductor

125 as at 136, and this conductor 135 includes a variable condenser 137. Leading from one end of the secondary winding 132 of the induction coil 128 there is a conductor 139 which is connected to the movable member 140 of a variable resistance 141, and one end of the primary winding 127 of the induction coil 128 is connected with this conductor 139 as at 141', by means of a suitable lead 142. The opposite end of the primary winding 127 is connected to ground by 10 means of a conductor 143. The opposite end to that heretofore mentioned of the secondary winding 132 of the induction coil 128 is connected by means of conductors 144 and 145 to the resistance element 146 of the variable resistance, and a fixed condenser 147 is interposed in this conductor. In this form of the invention the reference numeral 150 designates the first stage of radio frequency of a conventional receiving circuit and leading from the grid there- 20 of there is a conductor 151 which is connected to a conductor 152 having a movable switch element 153. This movable switch element 153 is adapted to contact with one of a plurality of points 154, 155, 156 and 157, and these points 25 are tapped upon a coil or winding 158. The fixed element 146 of the variable resistance is connected by a conductor 160 to the contact point 157, and the fixed element of the variable resistance, heretofore mentioned, is connected in 30 shunt with the winding L.

From the foregoing it will be apparent that the present invention provides in various modified forms, a tuned antenna circuit in which clearer signals, reduced interference, and greater 35 volume is obtained, and that in its broadest aspect these results are accomplished by reason of the fact that said antenna circuit includes one or more induction coils together with means for tuning the signal energy in each of the windings 40 of said coils, and while the invention has been herein disclosed in its preferred forms I do not wish to be specifically limited to the specific constructions illustrated since the invention may be carried out in other forms within the scope of 45 the appended claims.

Having thus described the invention, what is claimed as new, is:

1. An antenna circuit adapted to be built into a conventional radio receiving circuit, said antenna circuit including an inductance coil, having a primary and secondary winding a variable condenser electrically connected to both the primary and secondary winding and a variable resistance, a fixed condenser in series with said variable resistance, a connection connecting said variable resistance in shunt with the input of the first tube of a conventional receiver circuit and variably connected to both the primary and secondary winding of the inductance coil, an exterior antenna wire, and a switch for connecting and disconnecting said antenna wire to the primary winding of the inductance coil.

2. A double antenna circuit comprising in combination with a conventional radio receiver and its first vacuum tube stage, two antenna circuits each antenna circuit including an inductance coil, each of which coils includes a primary and a secondary winding, a variable condenser included in each antenna circuit for tuning the signal energy of the circuit, each of said variable condensers being connected to the primary and secondary winding of its respective inductance coil, means for controlling the volume before the signal reaches the first vacuum tube stage of the 75

5 said conventional radio receiver, said means including a variable resistance, said variable resistance being connected to the primary and the secondary windings of the antenna circuit, a plurality of antennae, and means for electrically connecting and disconnecting said antennae to one side lead of each primary winding.

10 3. A double tuning antenna circuit including two inductance coils, each having a primary and secondary winding the primary and secondary windings of one of said inductance coils being electrically connected respectively with the primary and secondary windings of the other of said inductance coils at a point intermediate of the 15 ends of said windings, and means for varying the signal energy of each inductance coil, said last mentioned means including a variable condenser electrically connected on one side to the primary windings of both of said inductance coils and 20 upon the other side to the secondary windings of both of said inductance coils.

25 4. In combination with a radio receiving circuit employing vacuum tubes, an antenna system including an antenna, an inductive coupling for connecting the antenna to the said receiving set, said inductive coupling including an inductance coil, including a primary and secondary winding a variable condenser connected to one lead of the primary winding of said inductance coil and to one lead of the secondary winding of the inductance coil, and means for electrically connecting the other lead of the primary winding of the inductance coil to the grid circuit of the first vacuum tube of the radio receiving circuit, means 30 for connecting the other lead of the secondary winding of said inductance coil to the ground circuit of the radio receiving circuit, and a variable resistance interposed between the antenna system and the said receiving circuit.

35 40 5. An antenna system comprising in combination with a radio receiving circuit including a vacuum tube, an inductance coil and a variable condenser, said antenna system comprising an inductance coil, including a primary and secondary winding a variable condenser connected to both the primary and secondary winding of the inductance coil, and means for connecting the antenna system to the receiving circuit, said means comprising a variable resistance electrically connected to and interposed between the

inductance coil of the receiver and the inductance coil of the antenna system.

5 45 6. In an antenna system, an antenna, an inductance coil, including a primary and secondary winding means for connecting one of the leads of the primary winding of said inductance coil to said antenna, a variable condenser connected to one lead of the primary winding and to one lead of the secondary winding of said inductance coil, a variable resistance connected in series to the 10 inductance coil and connected in shunt to the variable condenser, said variable resistance being variably connected to one lead of the primary winding and to one lead of the secondary winding of said inductance coil, a vacuum tube radio 15 frequency amplification circuit, said vacuum tube circuit including an inductance coil, a variable condenser shunt connected to the secondary winding of said second mentioned inductance coil, a condenser connected to one side of the 20 primary and to one side of the secondary winding of said second mentioned inductance coil, and means for connecting the antenna system to the primary winding of the inductance coil of the vacuum tube circuit, said means including said 25 variable resistance.

7. In an antenna system, including double antenna wires, two inductance coils, each of said inductance coils having a primary and a secondary winding, the primary and secondary winding 30 of one of said inductance coils having electrical connection with the primary and secondary winding of the other inductance coil, a variable condenser for each of said inductance coils, a variable resistance including a series condenser 35 variably connected to one lead of the primary and to one lead of the secondary of one of said inductance coils, a vacuum tube radio frequency amplification circuit, said vacuum tube circuit including an inductance coil, a variable condenser 40 shunting said inductance coil, and means for connecting the antenna system to the inductance coil of the vacuum tube circuit, said means including said afore-mentioned variable resistance shunt connected to the inductance coil of the vacuum 45 tube circuit, and a switch for each of said first mentioned inductance coils for connecting and disconnecting said double antenna wires with said first mentioned inductance coils.

JOSEPH RUIG RIGANDI. 50
